UNITED STATES PATENT OFFICE.

CHARLES TELLENBACH, OF BUTTES, SWITZERLAND.

WOOD-TURNING MACHINE.

Application filed September 14, 1925, Serial No. 56,837, and in Switzerland September 15, 1924.

The present invention relates to a process for turning out a very soft and tender wood wool representing the cuttings obtained in manufacturing wood-turned articles from 5 round timber.

- Machines for manufacturing ordinary wood wool having knives operating in the direction of the fibre are already known. They will produce a hard rough wood wool 10 consisting of fibres having a triangular or rectangular cross section and sharp edges. Here the wood or the tools are moved in an axial sense. Machines are already known for profiling or barking timber where this 15 latter is turned parallel to its axis before a cutter head having knives moving in a plane parallel to the axis of the timber. Here the cuttings are short hard chips and mostly used as combustible.
- 20 In the process according to the present invention a tool is used comprising a cutter head having straight blades rotated in a plane parallel to the axis of the timber, which is rotated parallel to its axis and presented to the knives at a point where they 25 operate on the timber surface in a helical path producing soft tender bands having a length exceeding that of the timber and a cross-section shaped like a segment of a circle.

The drawing represents machines adapted for performing the process according to the present invention.

- Fig. 1 is a sectional side elevation,
35 Fig. 2 is a front elevation and
Fig. 3 a plan of a first form and
Fig. 4 a side elevation of a second form.

Similar letters of reference indicate 40 similar parts. According to the Figures 1 to 3 a carriage *b* is slidably mounted on a bed *a* and is movable with the aid of rack and pinion from a hand wheel *c*. Arranged crosswise upon this lower carriage is an upper carriage *m* which carries the work piece 45 consisting of a piece of timber *l* between a dog *p* of a spindle stock *d* and the point *q* of the tail-stock *e*. A pulley *f* is serving as driving means for rotating the timber. The upper carriage *m* is pivotally supported upon

the lower carriage and may be held adjusted 50 at any angle to the lower carriage by means of a circular slot *n* and a clamping nut *o*.

The axis of a tool shaft *g* carrying at one end of the bed a driving pulley *h* and at the other end a cutter head-plate *i* is arranged parallel to and below the middle axis 55 of the lower carriage and within a vertical plane passing through said middle axis. The cutters *r* are straight blades sunk like plane-irons within slots *k* arranged tangentially to a circle having a diameter of about 60 a third of that of the plate *i*.

By advancing the carriage *m* towards the rotating cutter head *i* and rotating the timber *l* this latter will come into reach of the 65 blades, and the object to be turned which may be a spool or the like, will be shaped while the cuttings will assume the shape of thin, soft bands having a cross-section like a circular segment and a length exceeding that 70 of the timber. Thus a wood wool will be produced adapted like wadding for packing jewelry or confectionery.

The machine shown in Fig. 4 is in principle the same as that of Figures 1 to 3, but 75 here the tool shaft *g* is mounted in a separate part of the bed *a*. The disadvantage however exists that the shavings will easily be accumulated in the path of the cutter-plate.

What I claim is:

A process for obtaining wood wool while producing wood-turned articles said process consisting in rotating the timber parallel to its axis while presenting it to a cutter head rotating in a plane parallel to the axis 85 of the timber and having knives projecting from its radial face and of sufficient length for each knife to traverse the work from end to end and arranged with the axis of the work between the center and periphery 90 of said cutter head so that the knives operate on the timber helically in the direction of the grain the effect being to produce shavings having a meniscus-shaped cross-section available as a packing material like 95 wadding.

In testimony whereof I affix my signature.

CHARLES TELLENBACH.
